(57) CLAIM

The ornamental design for an insole for high heel shoes, as shown and described.

DESCRIPTION

FIG. 1 is a top plan view of a right insole for high heel shoes showing my new design;

FIG. 2 is a top, rear perspective view thereof; and,

FIG. 3 is a side view thereof.

The broken lines in the drawings illustrate stitching.

The bottom of the insole is devoid of surface ornamentation and a view thereof is omitted.
